His Attorney

UNITED STATES PATENT OFFICE.

JESSE G. KING, OF DAYTON, OHIO, ASSIGNOR TO DELCO-LIGHT COMPANY, OF DAYTON, OHIO, A CORPORATION OF DELAWARE.

REFRIGERATING APPARATUS.

REISSUED

Application filed September 26, 1923. Serial No. 664,810.

It is usual to associate with the expansion or refrigerating element of a refrigerating apparatus for use in residences, trays for containing water to be frozen into small blocks of ice for table use. These trays usually comprise relatively shallow open-top pans divided into a plurality of cells or ice compartments by crossed partitions giving a grid-like or checker-board appearance to the pans when viewed from above. Sleeves, constituting the walls of pockets for receiving the ice trays are generally formed in the brine tank (when brine tanks are used) within which the expansion coil 5 of the expansion or refrigerating element, (or "boiler" as it is sometimes designated) is inclosed. Usually the sleeves or tubular bodies referred to are surrounded by the turns of the expansion coil immersed in the 10 brine. Or if a brine tank is omitted, the sleeves or pockets for the ice trays are still disposed within the turns of the expansion coil but not in contact with brine. And in the latter case these sleeves or pockets may 15 extend from a cover plate or panel attached or lying close to that side of the coil that faces the front of the cabinet.

In operation water is apt to condense on the front of the brine tank, or the front 20 plate of the refrigerating coil, and runs downward thereon. It is one of the objects of this invention to prevent this condense water from entering the ice pans, since it may contaminate the ice, or overflow and 25 freeze the pan to the sleeve.

In case the ice pan freezes to the sleeve by reason of the cells having received so 30 much water that it overflows when congelation begins, or if for any other reason ice is formed within the sleeve in such position as to obstruct the withdrawal of the ice tray, breakage of the tray handle connections to the pan is apt to occur when an attempt is made to withdraw the tray in 35 order to harvest the ice. Another object of this invention is to enable broken connections occurring as described to be readily repaired.

The invention consists in the means hereinafter described and illustrated for preventing condense water from reaching the interior of the ice pan, and in details of 40 structure of the tray.

In the accompanying drawings, Fig. 1 is a vertical section through the refrigerating 55 compartment of a refrigerator cabinet exposing the refrigerating unit in side elevation, certain portions having been broken away to disclose the construction of essential features of this invention; and Fig. 2 is a horizontal section through a fragment of a brine tank, or a cover plate, disclosing a fragment of an ice tray in plan except that parts thereof are broken away.

In Fig. 1 the back of the outer shell or 60 casing of a refrigerating cabinet is indicated by 10, the top of said shell or casing by 11, the front by 12, and the door of the refrigerating compartment by 13. The front frame structure is shown at 14; 15 indicates 65 cork board insulation cemented to the sheet metal lining 16 of the compartment and spaced from the casing to form an air space 17; 18 is a channel bar, (of which there are in practice two) supported by the upper 70 cross member of front frame 14 and a cross cleat 19 on the casing back. Said channel bars sustain the bolts 20 which extend downward through holes in the web of the channel and are suspended by their heads from 75 said web. These bolts penetrate the cork insulation and the compartment lining; their lower threaded ends are passed through ears 21 on metallic straps or stirrups 22, which are suspended by nuts 23 on the ends 80 of the bolts below said ears, while spacing sleeves 24 on the bolts between the stirrups and the ceiling of the compartment prevent 85 any upward movement. The suspended stirrups constitute a cradle or bracket for positioning the refrigerating unit in the refrigerating compartment with ample space for permitting air to circulate around it.

In the embodiment illustrated a brine 90 tank is indicated by numeral 25. Within the brine tank, it will be understood, the usual expansion coil is inclosed. The front wall of the brine tank is indicated at 26. Extending inward and rearward from the front wall are sleeves or tubular bodies 27 forming pockets 28 for the ice trays. These 95 pockets have open front ends and are surrounded by and in direct contact with brine.

Ice trays having a relatively shallow pan 29 fit loosely within the pockets 28. The 100 pans are divided into a number of ice com-

partments 30 by the grid-like intersecting partitions 31. Spaced from the front of the brine tank between it and the door 13, is a front plate 32 that prevents access to the interior of the refrigerating compartment except to enable the ice trays to be inserted and removed. The front plate may be of metal coated with a porcelain or vitreous enamel, and suitably embossed as at 33 in 10 that part that is opposite the open ends of the pockets 28. In the embossed part 33 are orifices 34 registering with the open ends of pockets 28 and sufficiently large to permit the trays 29 to be passed through 15 them into the pockets 28 or withdrawn from said pockets through the openings.

Soldered or welded to the front end of each ice pan are two bosses 35, which are thus secured to the pan in such manner that 20 no obstruction is present on the inside to interfere with removal of ice. The bosses 35 are preferably of metal and may be of spool-like formation having their inner flanged ends secured to the tray by a mass 25 of soldering or welding metal as indicated at 36. Both bosses are drilled and countersunk and the drilled holes threaded as at 37. A flanged tubular anchor bolt 38 with a slotted head seated in the countersink is threaded 30 into the threaded hole in each boss and a slender, flat-headed machine screw 38^a is threaded into the center of each anchor bolt. The screws 38^a pass through countersunk holes in the flanges 39 of a looped handle 35 40, through a stop and cover plate 41 and through a separate spacer block 42, preferably of heat insulating material such as wood, inserted between the metallic stop and cover plate 41 and the metallic boss 35. 45 The stop and cover plate 41 is preferably dished, as shown, and its flange bears upon the front 33 when the tray is pushed into the sleeve. It is of a size and shape to cover the opening 34, preferably has the appearance 50 of a drawer or tray front and serves not only to close the opening but also as a stop and gauge to determine the position of the ice pan with respect to the pocket.

It will be observed that in the drawings 55 the front end of the pan does not extend beyond, nor flush with the front 26 of the brine tank, but occupies a position well within the pocket 28. In the position shown condense water or water formed by melting frost that may gather on the front of the brine tank will not run into the ice pan, but will drip across the space in front thereof. The bosses 35 and spacing blocks 42 are of such length as to space the front of 60 the ice pan from the stop plate 41 such a distance that when the stop plate engages the front 33, the ice pan will be housed entirely within the pocket. In building refrigerator cabinets and installing the refrigerating unit it is likely to happen that the

space between the front plate 33 and the front of the brine tank will not always be the same in each of several pieces of apparatus. By spacing said stop plates 41 from the front of the ice trays a distance 70 greater than the distance between the front plate 33 and the front 26 of the brine tank that is likely to exist in any refrigerator, the result will be that the front end of the ice pans will always be well within the 75 pockets 28, in any installation of one type when the stop plate 41 is pushed against the front plate 33. Thus, by no untoward accident in the course of manufacture will any refrigerating apparatus of the same type 80 have the ice pan in position to receive the drip of condense water or frost on the front of the brine tank when the handle is pushed in.

Although in Fig. 1 the invention is illustrated as applied to a refrigerating unit equipped with a brine tank, it will be obvious that it is also applicable to such a unit where the expanding coil is open, or not immersed in brine. The numeral 26 in Fig. 2 may be assumed to indicate a cover plate in the latter type of unit instead of the front wall of a brine tank, and the sleeve or tubular member 27 as extending rearward within the turns of the expansion coil. 85

In operation the cells or compartments 30 of the ice pan will be charged with water and the tray pushed into place with the pan seated within pocket 28. After the water has frozen, the tray may be withdrawn and the ice or so much as may be required removed from the pan. Should the tray be frozen to the walls of the pocket by reason of overflow of water from the pan or the freezing of water of condensation within the front opening of the pocket, it is possible that the bolts or screws 38, which are the weakest parts of the connecting links between the handle and the tray, 100 may become broken by the force exerted in attempting to withdraw the tray. If so, they may be readily replaced after first unscrewing the anchor bolt 38 by means of a spanner. A new anchor bolt and machine screw may then be readily fitted, avoiding the necessity of sending the tray to the factory or to a repair shop as has been necessary where other forms of fastening have 105 been used. 110

When the tray has been pushed into the pocket 28 until the flange of stop plate 41 engages the front 33, the front of the pan will be well within the pocket so that condense water that may run down the front of the brine tank (or cover plate as the case may be) will not enter the pan to contaminate the ice or overflow and freeze it to the sleeve. 125

Although I have described and shown a 130

preferred embodiment of my invention, it will be apparent that modifications thereof may be made within the definition of the appended claims without departing from 5 the principles of the invention.

What I claim and desire to secure by Letters Patent of the United States is:

1. In a refrigerating apparatus, a refrigerating unit, a pocket-forming sleeve 10 associated therewith, a tray for receiving water to be frozen adapted to fit within the sleeve, a front plate spaced from the entrance of the sleeve, said front plate having a tray-admitting opening registering with 15 the sleeve, a handle connected to the tray and a stop secured to the handle for engaging the front plate when the tray is in proper position within the sleeve, the distance between the front plate engaging portion 20 of the stop and the front of the tray being greater than the distance between the front plate and the front end of said sleeve.
2. In a refrigerating apparatus, a refrigerating unit, a pocket-forming sleeve 25 associated therewith, a tray for receiving water to be frozen adapted to fit within the pocket, a front plate having a tray-admitting opening registering with the sleeve, a handle carried by said tray for moving 30 the same into and for withdrawing the same from said sleeve, and a stop movable with said handle and tray and arranged to engage the front plate when the tray is in proper position within the sleeve, the distance 35 between the front plate engaging portion of the stop and the front of the tray being greater than the distance be-

tween the front plate and the front end of said sleeve.

3. In a refrigerating apparatus, a refrigerating unit equipped with a pocketed sleeve, an ice tray adapted to fit within the pocket, a boss secured to the front of the tray, a handle, a screw securing the handle to the boss, a separable heat insulating 45 spacing block surrounding the screw interposed between the handle and boss, and a stop plate movable with said ice tray and engaging a fixed member to limit the entrance of said tray into said pocket. 50

4. In a refrigerating apparatus, a cabinet having a refrigerating compartment, a refrigerating unit equipped with a pocket-forming sleeve installed within said compartment, a front plate spaced from the 55 front of said unit, said front plate having an opening registering with the front end of the sleeve; an ice tray adapted to fit within the sleeve, a handle, a boss on the front of the tray, an externally and internally 60 threaded anchor bolt secured in the boss, a removable spacing block in contact with the boss, a stop plate between the boss and the handle, adapted to engage the front plate and a screw threaded into the anchor bolt 65 and passing through said handle, stop plate and spacing block, the distance between the stop plate and front of the tray being greater than that between the front plate and the front end of the sleeve. 70

In testimony whereof I hereto affix my signature.

JESSE G. KING.
